UNITED STATES PATENT OFFICE.

WINFRED T. POWELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

1,387,174.

Specification of Letters Patent.

Patented Aug. 9, 1921.

Application filed August 16, 1918. Serial No. 250,179.

To all whom it may concern:

Be it known that I, WINFRED T. POWELL, a citizen of the United States, residing at East Orange, in the county of Essex, State 5 of New Jersey, have invented certain new and useful Improvements in Machine-Switching Telephone Systems, of which the following is a full, clear, concise, and exact description.

10 This invention relates to machine switching telephone systems and has particularly to do with overflow trunking arrangements in such systems.

15 The object of the invention is to provide means whereby a plurality of overflow trunks may be made common to a greater plurality of points from which an overflow trunk may be used, thereby effecting a saving in costly apparatus without decreasing 20 the efficiency of the system.

25 A feature of the invention is a novel organization of circuits and apparatus of well known commercial construction which, by certain changes in design, accomplish the object hereinbefore set forth.

30 It is broadly an arrangement of overflow trunks terminating at their outgoing ends in finder switches actuated in response to the overrun of selector switches by special overrun contact arrangements.

Specific features and points of novelty will be clearly described in the following specification and annexed claims.

In the drawings, Figures 1 and 6, taken 35 together, diagrammatically illustrate a path over which conversation may be held between a calling and a called substation, including in Fig. 1 a calling substation, an indicated line finder switch, a selector 40 switch, an overflow trunk ending in a finder switch, and in Fig. 6 the overflow trunk ending at its other end in a selector switch having access to an indicated connector switch in which the called line appears.

45 Figs. 7 and 6, taken together, diagrammatically illustrate a modified arrangement whereby a similar conversational path may be established. Fig. 7 contains the same elements as Fig. 1 and may be substituted 50 therefor.

Figs. 2 and 4 diagrammatically illustrate

the construction whereby contacts may be operated when the selector switch has failed to find an idle trunk and the overflow operation must be initiated. Fig. 2 shows an arrangement whereby there is one set of such springs for each group of contacts in the selector switch, and Fig. 4 shows the arrangement in which only one set of springs is used and may be adapted to be operated 60 on any trunk group.

Figs. 3 and 5 illustrate spring combinations which may be actuated for the purposes herein set forth.

In general, the operation of this system is 65 as follows:

A calling subscriber desiring to establish a connection with a certain substation, removes his receiver from its hook and manipulates his substation sender to set the 70 first selector switch in accordance with the first digit of the called line. This selector switch is thereby moved to select a certain group of trunk terminals and thereafter to automatically hunt for an idle trunk in this 75 group. If all of the trunks in the group are busy, then the selector switch moves its brushes to such a position as to actuate a certain spring combination which initiates the operation of a line finder switch associated with an overflow trunk. The line 80 finder switch thereupon connects with the selector switch which is moved to its overflow position and extends the line of the calling subscriber to a selector switch next 85 in order, which may be set in the ordinary manner by the calling subscriber.

Three methods for establishing a connection are shown in the drawings.

Figs. 1, 2, 3 and 6 illustrate the preferred method wherein there is a set of springs, 1 to 10, inclusive, for each of the ten groups of trunks appearing on the illustrated first selector switch. If this selector switch is directly set on the first group of trunks 90 and due to the busy condition of all the ordinary trunks, it moves to its overflow position, then the set of springs No. 1 will be actuated and the line finder switch associated with the idle overflow trunk will be 95 operated.

Figs. 4 and 5 illustrate a modification of

this arrangement, whereby a single set of springs is used. This set of springs may be associated with any one of the ten levels, the arrangement being for emergency use only 5 and such that the control of this set of springs may be shifted from one level to another.

Fig. 7 illustrates an arrangement wherein 10 the same result is accomplished through the use of an additional contact associated with the group of trunks on each level of the selector switch.

The selector switch shown in Fig. 1 is 15 of the type known as step-by-step, and comprises a set of brushes 23 adapted to move over and make contact with an arcuate bank of terminals. The brushes are moved in their primary direction to select a group by the primary magnet 20, and thereafter 20 rotated in their secondary direction by the secondary magnet 26.

The line finder switch shown at the bottom 25 of Fig. 1 is a rotary step-by-step mechanism, wherein the brushes stay where they are last set. It has no normal position, and the brushes always rest on some one set of terminals.

The selector switch shown in Fig. 6 is 30 similar to the selector switch shown in Fig. 1.

The selector switch shown in Fig. 7 is similar to that shown in Fig. 1 with the exception that as hereinbefore pointed out, it has no sets of springs to be actuated in the 35 overflow position, but has an extra contact leading to a relay which is the equivalent of the overrun contact arrangement shown in the selector switch of Fig. 1.

The line finder switch shown at the bottom 40 of Fig. 7 is in all respects similar to that shown at the bottom of Fig. 1.

The establishment of a connection from a calling to a called subscriber will now be fully described.

45 The calling subscriber at substation 11 removes his receiver from its switchhook, in response to which the line finder switch 12 will extend the calling line in the usual manner to a first selector switch 13, whereupon a line relay 14 will be energized over 50 a path including battery, the upper winding of relay 14, the contact 15 of the relay 16 to the calling subscriber's line, through the line finder switch 12, back to the contact 55 17 of the relay 16, the lower winding of relay 14, to ground. Relay 14 being energized in this circuit, attracts its armatures, and this establishes an energizing circuit for the first slow relay 18 over its alternate 60 contact and lower armature. First slow relay 18, in attracting its upper armature, grounds the test wire 19 in the usual manner for establishing the busy condition of the trunk to the first selector. First slow relay 65 18 also prepares a circuit for transmission

of impulses to the primary magnet 20, so that when the subscriber at substation 11 manipulates his dial switch and the relay 14 is thereby caused to vibrate its armatures in each back stroke of the lower one, a circuit will be established from ground, lower armature and normal contact of relay 14, contact 21 of relay 16, lower armature and alternate contact of first slow relay 18, through the winding of second slow relay 22, 75 winding of primary magnet PM, to battery and ground. As is usual in this well known circuit, second slow relay 22 responds to this series of impulses as a whole, and during their transmission retains its armature in its 80 attracted position. Primary magnet PM, however, responds separately to each impulse and moves the brushes 23 of the selector switch step by step in their primary movement.

85 Supposing through such directive action, the second level is selected, then at the end of the series of two impulses, relay 14 maintains its armatures energized, thereby opening the circuit for relay 22 and primary 90 magnet 22. During the time that relay 20 is energized and after the first step from normal of the switch 23, a circuit is closed from the ground placed, as described, on the test wire 19, through the armature and 95 alternate contact of relay 22, off-normal contact 24 and winding of relay 25, to battery and ground. Relay 25 is energized in this circuit and remains energized until after the relay 22 has retracted its armature, through 100 a circuit from the off-normal contact 24, the armature and contact of secondary magnet 26, the contact 27 of relay 25, to the test wire 19. As soon as relay 22 retracts its armature, a circuit is established from the ground 105 on test wire 19, through the armature and normal contact of relay 22, contact 28 of relay 25, the winding of secondary magnet 26 to battery and ground. Magnet 26 thereupon attracts its armature and impels the 110 brushes 23 forward in their secondary movement, one step. When the secondary magnet attracts its armature on its first step, the circuit for relay 25 is opened and it retracts its armatures, thereby opening the circuit 115 through the contact 28 for the secondary magnet and its own locking circuit, through the contact 27. If the brushes 23 encounter a busy trunk, however, the test brush 29 will find a ground on the terminal on which it 120 comes to rest and thereupon a circuit will be established from such a ground through the brush 29, contact 30 of relay 16, contact and armature of secondary magnet 26, off-normal contact 24, winding of relay 25, to battery 125 and ground. Relay 25 thereupon attracts its armatures the second time and establishes anew the previously described circuit for the energization of secondary magnet 26. Secondary magnet 26 becoming energized in 130

this circuit, moves the brushes 23 another step forward, whereupon the relay 25 is again deenergized.

These interactions will continue until an idle trunk is encountered or providing, as assumed in the present case, there are no idle trunks, then the brushes 23 will be stepped into the overflow position; thereupon the spring actuating member 31, secured to the shaft 32 of the selector switch, will actuate No. 2 set of springs.

The operation of this set of springs establishes a circuit from ground, the upper armature and contact of relay 14, spring 33 in the set 2, conductor 34, the contact 35 of the relay 36, winding of relay 37, to battery and ground. Relay 37 in attracting its armature, establishes a circuit from ground, its inner lower armature and contact, winding of relay 36, the armature and contact of magnet 38 and its winding, to battery and ground.

Assuming that the set of contacts on which the brushes 39 to 42 rest, is idle, a ground will be found on the terminal on which brush 39 rests, and will be connected through the lower armature and normal contact of relay 36, the lower armature and contact of relay 37, to the other side of the winding of relay 36, whereby the relay 36 is short-circuited. The magnet 38, however, is energized in this circuit and causes the movement of the brushes step by step over their associated terminals. When a set of terminals associated with the selector which is set by the overflow condition, is encountered, such as the first set of terminals shown, the ground connected to brush 39 will be absent due to the opening of the contact 43 in the set of spring contacts 2. In this case, the short circuit around relay 36 is removed and it becomes energized in series with the magnet 38. The resistance of the relay 36 and the magnet 38 is so adjusted that in this circuit the relay 36 will be energized, but magnet 38 will not be. Therefore, relay 36 will attract its armatures and in so doing, will break the energizing circuit of relay 37. Relay 37 being slow to release its armatures, will hold the ground on the winding of relay 36 until another ground can be substituted. Relay 36 in attracting its lower armature completes a circuit which may be traced from ground, inner lower armature and alternate contact of relay 37, alternate contact and lower armature of relay 36, brush 39 and its associated terminal, spring 43 in its actuated position, conductor 51, through the winding of relay 16, normal contact and armature of secondary magnet 26, contact 24 through the winding of relay 25 to grounded battery. Relay 16 is energized in this circuit but relay 25 is marginal and will not be operated.

When relay 16 attracts its armatures, it

extends the circuit from the calling substation through the brushes 41 and 42, and the two upper armatures of relay 36, to the selector switch shown in Fig. 6. Thereupon, relay 44 will become energized in a similar manner to the relay 14 and thereafter the first slow relay 45 will become energized and place a ground on the test wire 46, which will replace that furnished to the winding of relay 36 and the winding of relay 16 by the inner lower armature of relay 37. Through the attraction of the lower armature of relay 36, the ground from the upper armature and contact of relay 45 is communicated to the brush 39 and will mark the set of terminals on which these brushes now rest, as busy.

With relay 36 in its actuated condition, and relay 37 in its non-actuated condition, the starter wire 34 will be extended through the finder switch of Fig. 1 to the wire 47, which controls another finder switch, similar to that shown associated with another trunk extending in the direction of Fig. 6.

The operation of the selector switch shown in Fig. 6 is similar to that described in connection with the selector switch of Fig. 1 and hence will not be described in this case.

The subscriber at substation 11, having manipulated his substation sender, having set the selector switch in Fig. 1 in the second level of the trunk terminals, and having had his line extended thereby through the overflow action of the selector to the selector switch in Fig. 6, now manipulates his dial 95 to send the second series of impulses, whereupon brushes 49 will be set on a trunk leading to a connector switch indicated by the brush 50 which has access to the called line 51. Thereafter, the action is the same as in 100 any well known machine switching telephone system.

At the completion of the conversation, the selector switches are released in the well known manner through the removal of 110 ground from the test wire. When ground is removed from the test wire 46, the relay 36 will become deenergized and thereby remove the ground from the brush 39 and in turn from the conductor 51 leading to the 115 relay 16. Relay 16 becomes deenergized and thereby causes the closure of a circuit for the energization of release magnet 52 from battery and ground, winding of magnet 52, off-normal contact 53, normal contact and 120 lower armature of relay 18, contact 21 of relay 16, normal contact and lower armature of relay 14, to ground. Magnet 52 becoming energized, causes the restoration to normal 125 of the brushes 23.

In certain cases where by test it is found that only one particular level of a bank of multiple selector switches becomes overloaded, the modification indicated by Figs. 4 and 5 may be used. In this case the set 130

of springs 54 is associated only with that particular level which has been found to be overloaded. In place of the spring actuating member 31 secured to the shaft 32, there 5 is now a spring actuating member 55 with a multiple stop 56 attached to the shaft 32, whereby the spring combination 54 may be actuated only when the selector switch runs over on a particular level. When this happens, a line finder switch, similar to that 10 shown in the lower part of Fig. 1, is actuated in exactly the same manner as has been described, and the subscriber's line is extended to a trunk leading to the same group 15 as any one of the trunks on the level which has been directly selected.

In the arrangement shown in Figs. 7 and 6, a calling substation 57 may establish a connection with a called substation 51 20 through exactly the same method as before. However, if the brushes 58 associated with the selector switch 57 overrun, then instead of a set of contacts associated with the selected level being actuated, a circuit will be 25 established through an eleventh contact 59. In this case when the secondary magnet 60 has retracted its armature, a circuit will be set up from ground, the right-hand winding of relay 61, terminal 59, brush 62, the armature and contact 63 of relay 64, contact and 30 armature of secondary magnet 60, off-normal contact 65, winding of relay 66, to battery and ground. Relay 61 will be actuated in this circuit, but relay 66 will not. Relay 35 61 in attracting its left-hand armature removes the ground from terminal 67 to stop the non-numerical switch in engagement with said terminal in the manner described for the switch shown in Fig. 1. In attracting its 40 right-hand armature, relay 61 completes a circuit from grounded battery through the winding of relay 70, contact 71 of relay 72, conductor 68, right-hand armature and alternate contact of relay 61 to ground at the upper 45 per armature of relay 69. Relay 70 is energized in this circuit and starts the finder switch. As soon as relay 72 is actuated, in response to the completion of the function 50 of the finder switch in the manner hereinbefore described, a circuit will be completed from ground, the contact 73 of the relay 72, the brush 74, terminal 75, off-normal contact 76, the winding of relay 64 to and through the winding of relay 66, by the 55 path described. Relay 64 becomes energized in this circuit and extends the talking conductors from the calling line 57 through the finder switch and to the selector switch of Fig. 6. Through the movement of the upper 60 armature of relay 64, the brush 62 is grounded and the right-hand winding of relay 61 is short-circuited. Through the attraction of its armatures by the relay 72, the left-hand winding of relay 61 is also 65 short-circuited and it therefore retracts its

armatures. The further operation of the system is similar in all respects to that hereinbefore described.

What is claimed is:

1. In a telephone system, an arrangement 70 of overflow trunks terminating at the outgoing end in line finding switches, and selector switches having over-run contact arrangements for actuating said line finding switches.

2. In a telephone system, telephone lines, trunk lines, selector switches for interconnecting said telephone lines and said trunk lines, overflow trunk lines, line finding switches in which said overflow trunk lines terminate, and over-run contact arrangements 80 on said selector switches for actuating said line finding switches whereby said telephone lines and said overflow trunk lines may be interconnected.

3. In a telephone system, telephone lines, trunk lines, selector switches, said selector switches comprising sets of stationary contacts, and movable brushes for traveling over and making contact with said stationary 90 contacts, said selector switches interconnecting said telephone lines and said trunk lines via said movable contacts and said sets of stationary contacts, overflow trunk lines, line finding switches in which said overflow 95 trunk lines terminate, and over-run contact arrangements on said selector switches for actuating said line finding switches whereby said telephone lines and said overflow trunks may be interconnected.

4. In a telephone system, telephone lines, selector switches for extending said lines, said selector switches comprising movable brushes arranged to travel over and make contact with sets of stationary contacts, said sets of stationary contacts being arranged in groups, an over-run contact arrangement adapted to be actuated after said brushes have traveled over every set of contacts in a group, trunk lines arranged in groups and terminating in one end in said groups of sets of stationary contacts, and equivalent groups of trunks terminating at the corresponding end in line finding switches responsive to said over-run contact arrangements whereby said telephone lines and trunk lines may be interconnected.

5. In a telephone system, telephone lines, selector switches for extending said lines, said switches having trunks leading therefrom divided into groups of equivalent trunks, a secondary group of equivalent trunks common to each said group of trunks, each of said trunks of said secondary group terminating at one end in a line finding 120 switch, means for extending a connection from said telephone lines through the brushes in said selector switch to a trunk in a selected group, and means when no one of said trunks in said selected group is avail- 125 130

- able for extending said connection over one of said secondary trunks, said last means comprising a contact arrangement actuated on an over-run operation of said selector switch whereby one of said line finding switches is actuated to seek out that selector switch which has performed an over-run operation and extend said connection over one of said secondary trunks.
6. In a telephone system, selector switches comprising sets of stationary contacts arranged in groups, movable brushes arranged to travel over and make contact with said sets of stationary contacts, and over-run contact arrangements adapted to be operated when said brushes have traveled over all of the sets of contacts in any one group of said stationary contacts and come to rest in a position beyond any one of said sets of contacts, trunk lines leading from said sets of stationary contacts, equivalent trunk lines leading from said sets of stationary contacts, said equivalent trunk lines terminating at one end in non-numerical switches, said non-numerical switches being responsive to an actuation of said over-run contact arrangements whereby said telephone lines may be extended to said trunks via said brushes and sets of stationary contacts of said selector switches or to said equivalent trunks via said non-numerical switches.
7. In a telephone system, telephone lines, selector switches for extending said lines, said selector switches being arranged with movable brushes, and groups of sets of stationary contacts, means for imparting a group selecting movement to said selector switches, and means for thereafter imparting a contact set selecting movement to said brushes, said selector switches being provided with an over-run contact set individual to each group of said sets of stationary contacts, and means for actuating said over-run contacts at the end of said contact set selecting movement when said movement has resulted in the selection of no set of said stationary contacts, means responsive to the actuation of said over-run contacts for actuating one of a group of said non-numerical switches, whereby said telephone lines may be extended through said non-numerical switches.
8. In a telephone system, groups of telephone lines, a group of selector switches for each of said groups of telephone lines, the number of said selector switches in each group being less than the number of lines in the group which said group of selector switches serves, groups of non-numerical switches, each of said groups of non-numerical switches being common to said groups of selector switches and less in number than the selector switches which said groups of non-numerical switches serve, over-run contact arrangements on said selector switches for actuating said non-numerical switches, and means whereby said telephone lines may be extended either through said selector switches or said non-numerical switches.
- In witness whereof, I hereunto subscribe my name this sixth day of August A. D., 1918.

WINFRED T. POWELL.
